UNITED STATES PATENT OFFICE.

FRANK M. BOWMAN, OF BELLEVUE, AND ALEXANDER H. BOVARD, OF PITTSBURGH, PENNSYLVANIA, ASSIGNEES TO RITER-CONLEY MANUFACTURING COMPANY, OF PITTSBURGH, PENNSYLVANIA, A CORPORATION OF NEW JERSEY.

TRANSMISSION-TOWER.

1057,216.

Specification of Letters Patent.

Patented Mar. 25, 1913.

Application filed April 14, 1910. Serial No. 555,486.

To all whom it may concern:

Be it known that we, FRANK M. BOWMAN and ALEXANDER H. BOVARD, residents, respectively, of Bellevue and Pittsburgh, in the county of Allegheny and State of Pennsylvania, have invented certain new and useful Improvements in Transmission-Towers, of which the following is a specification.

10 Our invention relates to skeleton steel towers and particularly to towers of this class known as transmission towers and designed to support electrical transmission wires or cables.

15 In the embodiment of our invention as shown in the accompanying drawings and as preferred, our tower comprises a tapering pyramidal skeleton steel structure having four main upwardly converging corner 20 posts and a cross member designed for carrying any desired voltage arranged in two phases and each phase comprising three conductor wires.

An object of our invention is to provide a 25 tower of the character mentioned in which the four faces of the tower are of triangular form and of substantially the same dimensions and means for supporting all of the wires thereon outside of the corner 30 posts, thereby providing a tower combining a maximum of strength with a minimum of material.

A further object of the present invention is to provide new and improved means 35 acting with the tower proper for supporting the wires of the respective phases.

A still further object of our invention is to provide a construction in which the cross-arm or cross-arms of the tower are subjected in 40 to substantially no torsional stresses and in which the load of the upper wire of each triangularly arranged phase or circuit is not carried by the cross-arm or cross-arms of the tower.

45 In the accompanying drawings, which illustrate an application of our invention, Figure 1, is an elevational view of a tower embodying our invention; Fig. 2, a similar view taken at right angles to the view of Fig. 1; Fig. 3, a cross-sectional view taken on line III—III of Fig. 1; and Fig. 4, a enlarged perspective view of the upper portion of the tower.

Referring to the drawings and as preferred our tower comprises four corner 55 posts 2, preferably formed of angle-bars which are secured at their lower ends to legs 3 securely anchored in the ground by suitable anchor-plates 4. The lower ends of the corner posts are spaced equidistant 60 apart and converge upwardly in straight lines forming a pyramidal structure having four triangular faces of substantially the same dimensions. The four corner posts of the tower are connected at suitably 65 spaced intervals by horizontally disposed bracing members 5, as particularly shown by Fig. 3. In the tower illustrated we have shown three sets of these members indicated by the letters *a*, *b*, and *c*. In the horizontal 70 planes of the lower set *c* we employ diagonal brace-bars 6 extending inwardly from the four posts and meeting at and secured to a plate 7. The brace bars 5 of the set or series *a* are preferably connected by cross-members 8, while in the intermediate or set *b* we dispense with said members 6 and 8 and employ only the braces 5. In the upper series *a* we extend two of the bars 5 for a distance outside of two of the corner posts 80 and utilize this combined cross-arm and bracing construction for the support of telephone wires. The corner posts of the tower are further connected between the adjacent sets *b* and *c*; *a* and *b*; and between *c* and the 85 ground. Thus, between the ground and the lower braces 5 we provide on each face angle-bars or webs 9 extending from the lower ends of the posts 2 to a plate 10 to which they are secured, and members 11 and 12 connecting members 9 and the posts. Between the lower and intermediate brace-bars 5 the posts are connected by means of members 13 projecting upwardly and outwardly from the plates 10; and between the 90 intermediate and upper brace-bars 5 we employ for connecting the posts, members 14.

The converging upper ends of the corner posts are connected by means of members 15 and 16, and said members 15 are connected with a cross-arm 17. In the drawings, we have shown a single cross-arm preferably of channel form which extends through the tower and projects for a considerable distance from two faces thereof. Cross-arm 17

near its center is connected with the upper ends of the corner posts by means of the angle-bars 15 and the portions thereof lying outside of the tower are supported by a cantaliver construction in the form of a bracket composed of a combination of triangles. This cantaliver bracket construction constitutes an important and characteristic feature of our invention for it enables us to transmit the loads and stresses directly to the tower and relieves the cross-arm thereof.

The three wires of each circuit as illustrated are carried on pins 18 and these pins are arranged in the form of a triangle, preferably an equilateral triangle, with all of the pins located outside of the four corner posts of the tower. The two lower pins of each circuit are secured to the cross-arm 17, and the upper pin is carried by a mast preferably formed of two upwardly converging members 19 mounted on and secured to outwardly extending members 20 constituting a part of the cantaliver bracket construction. Members 19 are preferably of channel form and straddle the cross-arm 17 and are preferably tied together and to the cross-arm by a member 21. In addition to the members 20, which enter into the construction of one of the triangles of the cantaliver bracket, we provide members 22 and 23 respectively arranged in connection with a brace-bar 5 of the upper set of horizontal braces and with a member 24 to form two other triangularly shaped figures. We have indicated the triangles entering into the formation of the brackets by means of the letters *e*, *f*, and *g*, and have shown the largest triangle *e* braced by diagonal members 25. By this cantaliver construction the loads and stresses instead of being carried by the cross-arm or cross-arms are carried by the triangular bracing and by said bracing transmitted to the tower proper. It will be noted that the load, in the direction of the upper wire of each phase, is carried by the two members 19 alternately in tension and compression, depending upon the direction of the load on said wire, and that the stresses are carried by these two members to the cantaliver bracket and thence to the tower. It will be further noted that the stresses produced by the lower transmission wires of each circuit will be directly transmitted to the tower proper by the said triangularly arranged members.

In towers of this character it is usual to provide means for carrying and supporting a ground wire and for this purpose we have provided a superposed skeleton structure comprising four corner posts 26 secured to and extending upwardly from the corner posts of the tower proper. This upper structure corresponds to and is in effect a continuation of the pyramidal main tower so that the structure as a whole comprises four triangular faces extending from the points

of anchorage at the bottom to the ground wire connection at the top. The corner posts of the superposed structure or ground wire mast are suitably joined together at their converging upper ends by any suitable means, such for example, as clamping means similar to the clamping means 27 of the members 19; and the corner posts 26 are braced by members 28.

What we claim is:

1. In a skeleton tower construction, the combination with a tower, of a cross-arm projecting therefrom, a mast, and a cantaliver bracket construction for supporting the cross-arm and mast comprising two pairs of members each secured to two corner posts of the tower in substantially the same horizontal plane and extending therefrom to the cross-arm.

2. In a skeleton tower construction, the combination with a tower, of a cross-arm projecting therefrom, a mast comprising two converging members, and a cantaliver bracket construction for supporting the cross-arm and mast comprising two pairs of members each secured to two corner posts of the tower in substantially the same horizontal plane and extending therefrom to the cross-arm.

3. In a skeleton tower construction, the combination with a tower, of a cross-arm projecting therefrom, a mast comprising two converging members, and a cantaliver bracket construction for supporting the cross-arm and mast comprising two pairs of members each secured to two corner posts of the tower in substantially the same horizontal plane and extending therefrom to the cross-arm, said mast secured to one of the pairs of members and extending above the cross-arm.

4. In a skeleton tower construction, the combination with a tower, of a cross-arm projecting therefrom, and a cantaliver bracket construction for supporting the cross-arm comprising a pair of members secured to two corner posts of the tower and extending therefrom to an end of the cross-arm, a second pair of members secured to the said corner posts in substantially the same horizontal plane as the first mentioned pair of members and extending therefrom to the cross-arm at a point intermediate an end of the cross-arm and the tower.

5. In a skeleton tower construction, the combination with a tower, of a cross-arm projecting therefrom, a mast, and a cantaliver bracket construction for supporting the cross-arm and mast comprising a pair of members secured to two corner posts of the tower and extending therefrom to an end of the cross-arm, a second pair of members secured to the said corner posts in substantially the same horizontal plane as the first mentioned pair of members and extend-

ing therefrom to the cross-arm at a point intermediate an end of the cross-arm and the tower.

6. In a skeleton tower construction, the 5 combination with a tower, of a cross-arm projecting therefrom, and a cantaliver bracket construction for supporting the cross-arm comprising a pair of members secured to two corner posts of the tower and 10 extending therefrom to an end of the cross-arm, diagonal members connecting said pair of members, and a second pair of members secured to the said corner posts in substantially the same horizontal plane as the first 15 mentioned pair of members and extending therefrom to the cross-arm at a point intermediate an end of the cross-arm and the tower.

7. In a skeleton tower construction, the 20 combination with a tower, of a cross-arm projecting therefrom, a mast, and a canta-

liver bracket construction for supporting the cross-arm and mast comprising a pair of members secured to two corner posts of the tower and extending therefrom to an end 25 of the cross-arm, diagonal members connecting said pair of members, and a second pair of members secured to the said corner posts in substantially the same horizontal plane as the first mentioned pair of members and 30 extending therefrom to the cross-arm at a point intermediate an end of the cross-arm and the tower, said mast secured to the first mentioned pair of members of the bracket.

In testimony whereof we affix our signatures in presence of two witnesses:

FRANK M. BOWMAN.
ALEXANDER H. BOVARD.
